BY Charles G. Hensley
ATTORNEY.

UNITED STATES PATENT OFFICE.

JACOB L. KLEINMAN, OF NEW YORK, N. Y.

SLIDING AND SWINGING WINDOW.

Application filed May 19, 1927. Serial No. 192,713.

The present invention relates to windows and their frames, and it belongs to that class of device in which the sashes are adapted to slide vertically in their frame and also to be swung inwardly within the room. The object of the invention is to provide for a combination of sliding and hinged sashes in order that any degree of ventilation may be obtained from that of a slot opening caused by sliding one or the other of the sashes, up to an extreme opening wherein the sashes are swung inwardly within the room to provide an opening substantially equal to the size of the window frame. Another advantage of the present device is that the interior and exterior surfaces of the panes of glass contained in the sashes may be entirely cleaned from the interior of a room. Where the present device is employed, a person cleaning the windows is not subjected to any risk and the windows may be cleaned in less time than where the cleaner must reach out or stand outside of the window as with the ordinary sliding windows.

I am aware that windows have been proposed heretofore in which the sashes are adapted to both slide and swing inwardly, but the purpose of the present invention is to overcome the defects of such prior devices. One object of the present invention is to provide sliding and swinging sashes in the window construction and to make the device entirely weather-proof so that rain, snow or sleet cannot penetrate to the interior of the room when the sashes are closed. Another object is to provide a window of the character referred to which will efficiently exclude dust and which will not be rendered inoperative or difficult to operate in the event that dust penetrates between the moving parts.

Another object of the invention is to provide a window of the type set forth in which the window frame, as well as the sash frames, may be made of metal if desired, and this metal may be made in long or continuous strips and afterwards assembled into the type of structure shown in order that the cost of making the device principally from metal may be kept within rea-

sonable limits. Another object is to provide a window of the character described which will be easy to manipulate and which will not get out of operating order. Another object of the invention is to provide a window construction of the type described which will be neat in appearance when viewed either from the exterior or interior. Another object is to provide a window having sliding sash frames adapted to be placed in superposed or overlapping position, and while in that position the hinged members of the inner and outer sashes may both be swung into the room, the sections of the outer or upper sash opening into the spaces formed by the opening of the sections of the inner or lower sash. Another object is to provide a construction wherein the sashes will hide the sliding sash frame from view when the window is closed.

Other objects and advantages will be made apparent in the following detailed description of one embodiment of my invention.

In the drawings forming part of this application,

Figure 1 is an elevation of a window structure embodying my invention, looking at the same as viewed from the interior of the room,

Figure 2 is a vertical sectional view through the sashes and window frame,

Figure 3 is an elevation of a portion of the device showing the sash frames arranged in superposed relation with the sash sections swung inwardly,

Figure 4 is a sectional view taken on the line 4—4 of Figure 1,

Figure 5 is a sectional view taken on the line 5—5 of Figure 1,

Figure 6 is a sectional view taken on the line 6—6 of Figure 1,

Figure 7 is a sectional view taken on the line 7—7 of Figure 1,

Figure 8 is a sectional view taken on the line 8—8 of Figure 1,

Figure 9 is a sectional, perspective view taken on the line 9—9 of Figure 10,

Figure 10 is an elevation of a portion of the upper or outer sash,

Figure 11 is a plan view with parts of

the casing broken away and showing the parts in the same position as in Figure 3,

Figure 12 is a perspective view showing the sections of one of the sash frames swung partly open,

Figure 13 is an enlarged, perspective view showing portions of one of the sash frames and one of the hinged sash sections,

Figure 14 is a detail view of a portion of one of the sash frames in elevation,

Figure 15 is a view in plan of the same,

Figure 16 is an enlarged detail view of one of the corners of a hinged sash section,

Figure 17 is a sectional view showing in detail a portion of the sealing device at the side of one of the hinged sash sections,

Figure 18 is a sectional perspective view of the locking device for holding certain parts in locked position,

Figure 19 is a sectional view showing the engagement of the lock or latch of Figure 20 with a sash frame, and

Figure 20 is a perspective view of a lock or latch for holding the sash frames from sliding vertically.

In the drawings I have shown a metal frame or window casing comprising a bottom sill 1 a top sill 2 and side posts 3 all of which may be of metal formed to produce hollow members, one of which is shown adapted to receive portions of the sash members. The upper member 2 of the window casing is shown in cross section in Figures 1 and 4 and it consists of the four rectangular walls 4 one of which is provided with a longitudinal slot 5 facing downwardly, and which is formed by bending flanges 6 in the metal to extend inwardly within the pocket 7; and in the preferred construction, as shown in Figure 4, these flanges are slightly divergent, to receive a longitudinal flange 8 on the upper edge of the sash which closes the upper portion of the window. The flange 8 is adapted to slide in between the divergent flanges 6 the fit of the flange being rather close where it enters the opening 5 and being looser above this point, and the flange 8 projects above the flanges 6 when the upper sash is in its highest position so that if any dust should work its way in between the flange 8 and the flanges 6 it can work upwardly over the tops of the latter and thus discharge beyond these flanges. The lower or sill member 1 is also shown made of sheet metal with its top surface 9 inclining downwardly, and with a raised bead or rib 10 with which the lower portion of the lower sash is adapted to fit to make a water-proof, dust-proof and air tight joint.

The window frame is of sufficient dimensions to enclose the upper and lower sashes of the present construction. The window construction embodies a rectangular frame for the upper sash and a rectangular frame for the lower sash which move in different

grooves in the window frame and these frames are adapted to slide past each other. Each sash frame carries a pair of hinged units or sections in which the transparent members or glass panes are mounted. In

70

referring to the sashes I refer to the upper one as the one which is disposed in the higher position when the window is entirely closed, and to the lower one as that which is in the lower-

75

most position when the window is closed, although both sashes are adapted to slide vertically and at times they may be reversed in this relation.

80

For what I call the upper sash there is a rectangular frame comprising upper and lower horizontally disposed bars

85

11, 12 which are preferably made of channel metal and therefore U-shape in cross section, each having a vertically disposed web 13 provided with lengthwise extending beads

85

14 for stiffening the metal against bending action; and horizontally disposed webs 15 facing inwardly or toward the interior of the room. The lower horizontal bar 12 is

90

of similar construction and similarly disposed. These horizontal bars have projections 16 which have angular extensions 17 disposed at an angle to the plane of the members 16 and extending into slots 18 formed in the vertical members of the casement to

95

lie parallel and adjacent to the angular wall 19 which is formed from one member from which the vertical casement member is constructed. The members 17 are connected by the members 20 secured along their inner

100

edge, and which is adapted to slidily engage the cross wall 21 to guide the sash frame in its vertical movements and to prevent the extensions 16 from binding along the edges of the frame opening 18. These

105

members 20 form the vertical connections between the upper and lower horizontal bars of the sliding frame and, as shown, are enclosed in the casement. I have shown the vertical casement members 22 each formed

110

of a plate 21 forming the side wall, another plate 23 connected with it and forming the outer wall, which plate is also bent at an angle to form the wall 24

115

which faces the sashes and of which the walls 19, 21 are a continuation. In addition there is a plate 25 forming the inner wall of the casement member; and this is bent to form a recessed flange 26 of sufficient depth to receive a plate 27 as well as

120

one edge of an angular plate 28 so that both of these lie flush with the inner surface of the portion 24 as is shown in Figure 8. The plate 29 forms a part of the guideway of the

125

sash frames and the plate 28 which is attached to it forms at 30 one of the guideways for the sash frames. The plate 28 extends inwardly at an angle as shown at 31

130

and is then bent again at an angle as shown at 32 to form a groove to receive the edge

130

of the plate 21. There is a vertical slot 32 formed between the plates 29, 27 and vertical pockets 30, 33 are formed by the several plates above described in which the guiding and sealing portions of the sashes travel.

The sliding frame for the lower sash member is constructed similar to the frame of the upper sash member and therefore it contains the horizontally disposed channel bars 11 and 12 which have extensions 35 which are connected securely at their ends to the vertical bars 36. The extensions 34 extend through the slots 32 in the casement members, and the connecting members 36

channels corresponding with the offsets 43. This bar also has a horizontal web 74 which carries the flange 54 to receive the upper edge of the interlocking flange 53 on the 5 lower bar of the upper sash member. The tops of the members 48 and 54 are flush, the flange 53 being short enough to allow the parts to come into the position shown in Figure 6. The sash sections C and D also 10 have a lower bar 75 having a downwardly extending flange 76 which tightly engages the rib 10 on the lower sill when the window is in closed position. To the horizontal web 77 of this bar there is secured a 15 plate which has a downwardly extending flange 78 which engages and fits snugly to the inner surface of the rib 10. This bar also has a vertical web 79 provided with the offsets 80 forming horizontal grooves to 20 correspond with the offsets 43. There is a horizontal web 81 and there is an upwardly extending flange 82 against which the lower edge of the glass 69 is clamped by the securing strip 83. The sash sections C 25 and D are similar to each other, except for the fact that they are made right and left and except for the differences in the vertical strips along their meeting edges. In regard to the latter feature, it may be pointed out 30 that the section D has a strip 56 along the meeting edge which is in all respects like the strip 56 on the upper sash section B and the section C has a strip 60 in all respects corresponding with the strip 60 on the upper sash sections A; which strips overlap 35 and interlock when the sash sections C and D are closed, the same as the corresponding strips of the upper sash sections, thereby forming a weather-proof and dust-proof 40 joint along the vertical center of the sash sections when the latter are in closed position. The lower sash sections C and D each have flanges 84 extending in reverse directions at the sides of the sash sections adjacent the pivotal pins 67 and these flanges are adapted to project into the slots 32 of the casement members when the sashes are 45 in closed position, or when they are swung into the same horizontal plane; and prevent 50 air, moisture and dust from passing around the sides of the sash and reaching the room; whereas these side flanges withdraw from the slots 32 when the sash sections are 55 opened to the position shown in Figure 11.

I have shown in Figure 18 a latch or lock consisting of a plate 85 swinging on a pin 86 and provided with a finger grip 87. This latch has a hook portion 88 adapted to engage a pin 89 for the purpose of holding 60 the members A, B, or C, D in locked engagement. Preferably, one of these latches is provided at the top of the upper sash section or at the top of the section A, another at the bottom of this section A, and still 65 another at the top and bottom of the sash section B, all of these latches being alike in construction. They serve the purpose of locking the sashes A and B to the sliding frame to prevent the sections from swinging inwardly except when the latch is released, 70 and they also serve to prevent the sections C and D from swinging inwardly except when the latches are released. If desired, jointed, pivoted links 90 may be attached respectively to the upper sliding frame and to the swinging sections A and B for bracing the latter in open position and similar jointed links 91 may be attached respectively to the lower sliding frame and the corresponding sash sections C 75 and D for bracing the latter in open position. These several links are adapted to fold into the horizontal channel bars of the sliding frame.

When the window structure is placed in 80 closed condition, the sash sections A and B form the closure for the upper half of the window and the sections C and D form the closure for the lower half of the window as shown in Figure 1, and the several bars have 85 the appearance or finish of moulding. When the sash frames and sashes are in the position shown in Figures 1 and 2 the window is entirely closed and is held so by the several 90 latches or locks hereinabove described. The flange 8 on the upper sash projects into the slot 5 so that at this point the window is weather-proof, wind-proof and substantially 95 dust-proof. Where the upper and lower sashes meet a joint formed by the flanges or lips 54, 53 makes a weather-proof, moisture- and dust-proof connection. At the bottom 100 the members 76, 78 straddle and contact with the rib 10 on the lower sill, rendering the joint here proof against moisture and dirt. The overlapping and interlocking members 105 56, 60 of the upper sash members A and B form a weather-proof and dust-proof connection along the medial line of the upper window sash and the corresponding members on the lower sash members C and D form a similar joint at the medial line of the lower half of the window. The flanges or wings 110 66 project into the slots 18 on the side posts of the casement and prevent the entry of moisture and dust around the side edges of the several sash members. The flanges 84 enter the slots 32 and serve the same purpose for the lower sash.

With the sash frames arranged in the position shown in Figures 1 and 2, the upper sections A and B may be swung open by first swinging open the section A and then the section B, the locks or latches being released for this operation. In this instance 115 the sections will be swung into the room, as shown in Figure 12, so that the upper half of the window may be partly or fully opened. Likewise the lower sashes C and D may be 120 swung inwardly in the same manner and if 125 65 another at the top and bottom of the sash

all four sections are opened, the entire window will permit of maximum circulation of air. When the several sections A, B, C, D are in closed position in relation to their 5 sliding frames, the sliding frames and their respective sashes may be slid vertically in the guiding grooves 18, 32 and if desired they may be brought to the position as shown in Figure 3, and then all four of the sash 10 sections may be opened. To accomplish this, the sash sections C, D are first opened inwardly and then the sections A, B may be swung inwardly within the opening formed by the swinging of the sections C, D. As 15 the sections A, B are slightly shorter than the sections C, D, and as is shown in Figure 3, and as the pivotal points of the sections A, B are slightly closer than the pivotal points of the sections C, D the opening of 20 one set of sash members within the other, as illustrated in this view, is made possible.

The members 10^a (Figure 10) beyond the 25 pivots 55 are merely dummy extensions having the appearance of continuations of the horizontal bars of the upper sash sections. The latter, it will be remembered, have their pivots 55 closer than the pivots 67 of the lower sash sections.

In cleaning the glasses in the several sections the sliding frames may be moved into 30 the position shown in Figure 3, and the inner surfaces of the sections C, D may be first cleaned before any of the sections are opened, and then the sections C, D may be opened or 35 swung inwardly, whereupon the outer surfaces of the glasses in these sections may be cleaned within the room. The inner surfaces of the glasses in the sections A, B are then accessible from within the room for cleaning, and after these surfaces have been 40 cleaned, the sections A, B may be swung inwardly to the position shown in Figure 3, whereupon the outer surfaces of the glasses in sections A, B may be cleaned within the 45 room.

From the above it will be apparent that 50 all portions of the sash members may be readily cleaned from inside the room. Furthermore, ventilation may be secured either by sliding the upper or lower sash or both, or by swinging any or all of the sash sections inwardly.

While I have illustrated and described the 55 preferred embodiment of my invention, it will be understood that changes may be made in the details thereof without departing from the spirit of the invention and I desire to be limited only by the state of the prior art and the appended claims.

Having described my invention, what I claim is:

1. A device of the class described comprising a casement having guide slots, a sliding sash frame guided by said casement, a sash

composed of hinged sections having flanges adapted to project into the slots in said casement.

2. A device of the class described comprising a casement having slots, a sliding sash frame guided by said casement, a sash 70 composed of sections pivoted to said sliding frame, said sash sections having projecting flanges arranged near the pivots of said sash sections, said flanges being adapted to project into the slots in said casement. 75

3. A device of the class described comprising a casement having slots, a sliding sash frame guided by said casement, a sash comprising sections pivoted to said sliding frame and flanges projecting from said sash sections adjacent their pivotal points, said flanges being adapted to project into the slots of said casement when the sashes are in closed position, and to withdraw from the said slots when the sashes are swung at an 85 angle to their sliding frame. 80

4. A device of the class described comprising a casement having slots, a sliding sash frame having projections extending into said slots, a sash composed of sections pivoted to said sliding frame, and flanges on said sash sections adjacent the pivots of the sash sections and adapted to extend into said slots of the casement. 90

5. A device of the class described comprising a casement having slots, a plurality of sash frames guided to move in separate paths by said casement, sashes pivotally mounted on each of said sash frames and composed of separate hinged sections adapted to be swung at an angle to the respective sash frames, and flanges projecting from said sash sections and adapted to extend into the slots in said casement. 95

6. A device of the class described comprising a casement having slots, a plurality of sash frames guided to move in separate paths by said casement, sashes pivotally mounted on said sash frames and composed of separate hinged sections and adapted to be swung 105 at an angle to the respective sash frames, flanges projecting from said sash sections adjacent their respective pivotal points and adapted to extend into said slots in the casement when the sash sections are closed, and 110 to withdraw therefrom when the sash sections are swung into open position. 115

7. A device of the class described comprising a casement having slots, a plurality of sliding sash frames guided to move in separate paths by said casement, sashes mounted on said sash frames and composed of separate hinged sections, the sections of one of said sashes being relatively smaller than those of another sash and projecting flanges 120 on said sash sections adjacent their pivotal points and adapted to move in arcuate paths into said slots in the casement. 125

8. A device of the class described comprising a casement having a plurality of vertical slots, a plurality of sliding sash frames having projections extending into said slots, 5 sashes pivotally mounted on said frames and composed of separate hinged sections adapted to be swung in relation to the respective frames, said sash sections having projecting flanges adjacent their pivotal points adapted 10 to extend into said slots.

9. A device of the class described comprising a casement having slots in their opposed guiding surfaces and having guiding walls angularly disposed in relation to said opposed surfaces, a plurality of sliding sash frames having means extending into said slots and co-operating with said angular guiding walls, and sashes pivotally mounted on said sash frames and composed of separate hinged sections adapted to be swung at 15 an angle to the respective sash frames, said sash sections having flanges adapted to extend into said slots in the casement.

10. A device of the class described comprising a casement having side posts provided with vertical slots in their opposed sides, walls in said posts forming separate guiding compartments with each of which one of said slots communicates, a plurality 25 of sliding sash frames guided by said posts and having members extending into said slots, sashes pivotally mounted on said frames and composed of hinged sections adapted to be swung in relation to said sash frames.

11. A device of the class described comprising a casement having side posts provided with vertical slots in their opposed sides, walls in said posts forming separate 40 guiding compartments with each of which one of said slots communicates, a plurality of sliding sash frames guided by said posts and having members extending into said slots, sashes pivotally mounted on said frames and composed of hinged sections adapted to 45 be swung in relation to said sash frames and flanges on said sash sections adapted to project through said slots in the casement and to move in said compartments.

50 12. A device of the class described comprising a casement, a plurality of sliding sash frames guided to move in separate paths by said casement, sashes pivotally mounted on said sash frames, and means 55 forming interlocking engagement between the lower portion of the upper sash and the upper portion of the lower sash, comprising an upwardly projecting flange on one of said sashes and a grooved member on the other sash interlocking with said upwardly 60 extending flange.

65 13. A device of the class described comprising a casement formed of sheet metal and including a bottom sill member formed to provide an upwardly extending rib, sash

frames guided by said casement, sashes carried by said frames, and a plurality of flanges on the lower sash adapted to engage against the inner and outer surfaces of said rib on the casement.

70 14. A device of the class described comprising a casement formed of sheet metal and including a top member of hollow cross section having a slot in its lower surface and provided with flanges extending upwardly 75 from the edges of said slot, sash frames guided by said casement, sashes in said frames, and a flange at the top of the upper sash adapted to extend into said casement slot.

80 15. A device of the class described comprising a casement formed of sheet metal and including a top member of hollow cross section having a slot in its lower surface and provided with flanges extending upwardly 85 and inwardly from the edges of said slot, sash frames guided by said casement, sashes in said frames, and a flange at the top of the upper sash adapted to extend into said casement slot.

90 16. A device of the class described comprising a casement, a sliding sash frame of rectangular form guided by said casement, said sliding frame having cross bars of angle metal construction, a sash pivotally connected to and carried by said sliding frame and having cross bars of angle metal construction adapted to overlap the cross bars of said sliding frame when the sash is 95 in closed position.

100 17. A device of the class described comprising a casement, a sliding sash frame of rectangular form guided by said casement, said sliding frame having cross bars of substantially 105 U-shape cross section disposed with the intermediate web in vertical position, a sash hinged to and carried by said frame and having cross bars of substantially U-shape cross section disposed similar to and adapted to overlap said cross bars of the 110 sliding frame when the sash is in closed position.

115 18. A device of the class described comprising a casement, a sliding frame of rectangular form guided by said casement, said sliding frame having cross bars of substantially 120 U-shape cross section with the parallel webs horizontally disposed, a sash hinged to said sliding frame, having cross bars of substantially U-shape cross section adapted to overlap the cross bars of said sliding frame and having offsets adapted to receive the edges of the horizontal webs of the cross bars of said sliding frame.

125 19. A device of the class described comprising a casement, a sliding sash frame of rectangular form guided by said casement, said sliding frame having cross bars with substantially U-shape cross section with the parallel webs horizontally disposed and hav-

ing longitudinal corrugations in the vertical web, and a sash pivoted to said sliding frame and having cross bars adapted to overlap the cross bars of said sliding frame.

5 20. A device of the class described comprising a casement, a sliding sash frame of rectangular form guided by said casement, said sliding frame having cross bars of substantially U-shape cross section with the parallel webs horizontally disposed, a sash pivoted to said sliding frame and having cross bars of substantially U-shape cross section with the parallel webs horizontally disposed and adapted to overlap and closely 70 fit the parallel webs of the cross bars of said sliding frame.

21. A device of the class described comprising a casement, a sliding sash frame of rectangular form guided by said casement, 20 said sliding frame having cross bars of substantially U-shape cross section with the parallel webs horizontally disposed, a sash comprising a plurality of sections hinged at opposite sides to said sash frame, said sections having cross bars of substantially 25 U-shape cross section adapted to overlap the cross bars of said sliding frame when the sash sections are closed.

22. A device of the class described comprising a casement, a sliding sash frame guided by said casement, a sash composed of sections hinged at opposite sides to said sliding frame and angle metal bars arranged along the meeting edges of said sash sections, 35 said bars being formed to provide tongues and grooves which interlock in overlapping relation when said sash sections are in closed position.

23. A device of the class described comprising a casement, a sliding sash frame guided by said casement, a sash comprising sections hinged at opposite sides of said sliding frame, said sliding frame having cross bars, said sash sections having cross 45 bars overlapping the cross bars of the sliding frame and said sash sections having vertical bars along their meeting edges, said latter bars having longitudinal corrugations to provide tongues and grooves adapted to 50 interlock when said sash sections are closed.

24. A device of the class described comprising a casement, a sliding frame guided by said casement and having cross bars of substantially U-shape cross section, hinged 55 sash members pivotally connected at opposite sides to said sliding frame and pivoted arms connected between said sash sections and the cross bars of said sliding frame to limit the swing of the sash sections and 60 adapted to fold within the cross bars of said sliding frame.

25. A device of the class described comprising a casement provided with guiding slots therein, a sash frame having means extending into and guided in said slots of the

casement, a sash composed of hinged sections mounted on said sliding frame, said sash sections having flanges extending into said slots when the sash sections are in closed position, said sash sections being adapted to 70 overlap and hide said sliding frame from view when in closed position.

26. A device of the class described comprising a casement, a sliding frame guided to move in said casement, a sash composed 75 of sections pivoted to said sliding frame, said sash sections having vertically disposed overlapping bars having ribs extending into each other, at least one of said bars having an in-turned flange adapted to overlap the 80 bar of the other sash section and to extend adjacent the glass of said latter section.

27. A device of the class described comprising a casement having separate compartments, said casement formed with openings 85 communicating with said compartments, one wall of said compartment being angularly disposed with relation to the other walls, a sliding frame having means extending through said openings into said compartments, said means being guided by said angularly disposed walls and means to prevent the displacement of said sliding frame from said casement.

28. A device of the class described comprising a casement having slots therein, frames adapted to slide in said slots and sashes pivotally mounted on said frames, 95 said sashes being so disposed as to hide said frames from view when in closed position. 100

29. A device of the class described comprising a casement having slots formed therein, frames adapted to slide in said slots, said frames including a cross piece, said cross piece formed with a reduced end portion, and an opening near said reduced end, a sash carried by said sliding frame having an opening at one of its ends, a pin mounted in the openings in said sash frame and sash permitting said sash to pivot on said frame, 110 the end of said sash adapted to engage the said reduced portion of the cross piece in its pivotal movement.

30. A device of the class described comprising a casement having slots formed 115 therein, frames adapted to slide in said slots, said frames including a cross piece, said cross piece formed with a reduced end portion and an opening near said reduced end, a sash carried by said sliding frame having an opening at one of its ends, and a pin mounted in the openings in said 120 sash frame and sash permitting said sash to pivot on said frame.

31. A device of the class described comprising a casement, frames mounted on said casement including cross bars, sashes pivotally mounted on said frames and means carried by said cross bars and sashes adapted to interlock when said parts are in closed position. 130

32. A device of the class described comprising a casement, frames mounted slidably on said casement including cross bars, sashes pivotally mounted on said frames, a pin carried by said cross bars and means carried by said sashes to engage said pin when in closed position. 70
33. A device of the class described comprising a casement, frames mounted slidably on said casement including cross bars, sashes pivotally mounted on said frames, a pin carried by said cross bars, and a bevelled bar carried by said sashes adapted to engage said pin when said parts are in closed position and to lock the same. 75
34. A device of the class described comprising a casement, frames mounted slidably on said casement including cross bars, sashes pivotally mounted on said frames, a pin carried by said cross bars and locking means carried by said sashes, said means comprising a plate having a hooked portion adapted to engage said pin. 80
35. A device of the class described comprising a casement, frames mounted slidably on said casement including cross bars, sashes pivotally mounted on said frames, a pin carried by said cross bars and locking means on said sashes comprising a plate having a hooked portion adapted to engage said pin, said locking means being provided with means for grasping the same. 85
36. A device of the class described comprising a casement, frames slidably mounted on said casement including cross bars, said cross bars formed with a channel portion, sashes pivotally mounted on said frames and means for interlocking said bars and sashes pivotally mounted thereon and extending within said channel portion. 90
37. A device of the class described comprising a casement, frames slidably mounted on said casement including cross bars, said cross bars formed with a channel portion, sashes pivotally mounted on said frames, a pin mounted within said channel portion and locking means carried by said sashes comprising a hooked member pivotally mounted thereon and extending within said channel portion and adapted to engage said pin. 95
38. A device of the class described comprising a casement, frames slidably mounted on said casement, sashes pivotally mounted on said frames, said sashes including a longitudinally formed beaded portion and a device mounted on said sashes to finish off the ends of said beaded portion and so shaped as to permit the pivoting of said sashes. 100
39. A device of the class described comprising a casement, frames slidably mounted on said casement, including cross bars, sashes pivotally mounted on said frames including cross bars, the cross bars of said sashes having cutout portions at its pivoted end to permit the swinging of said sashes and means mounted on the cross bars of said frames to engage and interlock with the cutout portions on said sashes when in closed position. 105
40. A device of the class described comprising a casement, frames slidably mounted on said casement including cross bars, sashes pivotally mounted on said frames, 75 said sashes formed of channel portions, means pivotally mounted within said channel portions adapted to engage said cross bars when in closed position for locking the parts. 110
41. A device of the class described comprising a casement, frames slidably mounted on said casement including cross bars, pins carried by said cross bars, sashes pivotally mounted on said frames, said sashes formed of channel portions and means pivotally mounted within said channel portions adapted to engage the pins on said cross bars when in closed position for locking the parts. 90
42. A device of the class described comprising a casement, frames slidably mounted on said casement including channel portions, sashes pivotally mounted on said frames including channel portions, and means carried by said channel portions adapted to interlock with each other when in closed position. 95
43. A device of the class described comprising a casement, frames slidably mounted on said casement including channel portions, a pin carried by said channel portion, sash pivotally mounted on said frames, including a channel portion, and means carried by said latter channel portion adapted to engage said pin when in closed position 100
- for locking the parts. 105
44. A device of the class described comprising a casement, frames slidably mounted on said casement, sashes pivotally mounted on said frames, said sashes provided with cut-out portions, means for locking said frames and sashes mounted within said cut-out portions. 110
45. A device of the class described comprising a casement, frames slidably mounted on said casement, sashes pivotally mounted on said frames, said sashes provided with cut-out portions, means for locking said frames and sashes mounted within said cut-out portion, said means provided with a portion disposed above said cut-out portion. 115
46. A device of the class described comprising a casement, frames including outer and inner surfaces slidably mounted on said casement, sashes including outer and inner surfaces pivotally mounted on said frames, and locking means mounted on the inner surface of one of said sashes for locking said sashes and frames, said locking means 120

- 130

being disposed remote from the outer surface of one of said frames when in closed position.

47. A device of the class described comprising a casement, upper and lower frames including outer and inner surfaces slidably mounted on said casement, upper and lower sashes including outer and inner surfaces

pivottally mounted on said frames, and locking means mounted on the inner surface of the upper sash, said locking means being disposed remote from the outer surface of the lower frame when in closed position.

Signed at the city, county and State of New York the 5th day of May, 1927.

JACOB L. KLEINMAN.
